United States Patent Office

Des. 212,607
Patented Nov. 5, 1963

212,607

CASKET

Richard Rittenhouse, Rosemont, Pa., assignor to Union Casket Company, Wilmington, Del., a corporation of Delaware

Filed Mar. 6, 1968, Ser. No. 10,861

Term of patent 14 years

(Cl. D19—1)

FIG. 1.

FIG. 2.

FIG. 3.

FIG. 4.

FIG. 5.

FIG. 6.

FIG. 1 is a right side view in elevation of a casket embodying my new design;

FIG. 2 is a left side view in elevation of the casket of FIG. 1;

FIG. 3 is a top plan view of the casket of FIG. 1;

FIG. 4 is a bottom plan view of the casket of FIG. 1;

FIG. 5 is a right end view of the casket of FIG. 1; and

FIG. 6 is a left end view of the casket of FIG. 1.

I claim:

The ornamental design for a casket, as shown.
